[57] CLAIM

The ornamental design for a body section of a bottle, as shown and described.

DESCRIPTION

FIG. 1 is a front elevational view of a body section of a bottle showing our new design, the opposite elevational view being a mirror image thereof; and, FIG. 2 is a top front perspective view thereof. The broken line disclosure of the bottle is for illustration of environmental structure only and forms no part of the claimed design.

FIG. 1

FIG. 2
